UNITED STATES PATENT OFFICE.

WILLIAM A. HUNT, OF HOLDEN, WEST VIRGINIA.

RAIL-TIE CONNECTION.

Application filed October 2, 1928. Serial No. 309,757.

This invention relates to a rail tie connection which can be used for laying permanent track where the latter is connected to temporary track and which can also be used 5 for laying temporary track.

One object of my invention is to facilitate the advancing of the track, for example, in a mine, when the track is extended only a short distance at a time.

10 Another object of my invention is to provide means for clamping together the permanent track and the temporary track, where they meet, in a quick and sure manner, which means can also be used for securing the temporary track in position beyond the permanent track.

I attain my object by providing in combination with a rail tie, a fixed abutment against which the base of the rail of the 20 temporary track is held, and a reversible member adapted to hold the ball portion of the temporary rail or to fasten the permanent track to the tie when the rail of the latter track holds the ball portion of the 25 rail of the temporary track.

In the accompanying drawing, illustrating a preferred embodiment of my invention, Fig. 1 shows my rail tie connection when the rails of the permanent and temporary 30 tracks are clamped together,

Fig. 2 shows my rail tie connection when the rail of the temporary track is clamped in position beyond the permanent track.

Coming now to a description of my invention, rail ties 1 have secured to them angular abutments 2 by means of rivets 3. Reversible clips 4 are rotatably secured to ties 1 by means of rivets 5. This arrangement permits the clips 4 to be turned around so that 40 they can be used in two different ways, as shown by Figs. 1 and 2.

Each of the clips 4 comprises an inclined clamping toe 6 and a jaw member 7 having two jaws 8 and 9.

45 Referring particularly to Fig. 1, the rail T of the temporary track is clamped between abutment 2 and the rail R of the permanent track, and the rail R is clamped between the clip 4 and the rail T. In this instance, the base 10 of rail T is held against abutment 2, and the ball portion 11 of rail T is held between the ball portion 12 and base 13 of rail R.

To loosen this connection all that is necessary is to tap the clip 4 at 7. This will cause 50 the clip to swing around on rivet 5. Now

rail T may be advanced by sliding it along. When rail T has been advanced sufficiently, it may be clamped to rail R again in a new position with respect to the latter. The 60 clamping is done by tapping clip 4 at 7 so that clamping toe 6 engages base 13.

When my rail tie connection is used with only the temporary track, as shown in Fig. 2, the clip is turned around so that its jaws 65 embrace the ball portion 11 of rail T. In this case, the jaw 8 supports the ball portion 11 and the jaw 9 holds it down against jaw 8. To unfasten this connection all that is necessary is to tap toe 6, and the clip will then 70 swing out of engagement with the ball portion 11. The rail can now be advanced, after which it is clamped again between clip 4 and abutment 2.

This invention is particularly useful in 75 mines where it is necessary to bring the mine car close up to the working face at the end of the tunnel. As the working face is advanced, the track must be advanced. Heretofore it was customary to add short pieces of 80 track in order to bring the same up to the working face. This method is very slow and produces a bad track.

With my invention it is possible to use a single size rail throughout. When the distance between the end of the permanent track and the working face of the tunnel is less than the length of a rail, the latter is laid on its side, as shown in Fig. 1, and advanced up to the working surface. Where the temporary 90 track and permanent track overlap they are clamped together, as in Fig. 1. The rim 16 of the mine car wheel rests on the ball 12 of the rail R when the car is over the permanent track. As the car comes over the temporary 95 track, the flange 14 of the car wheel will rest on the neck 15 of rail T. In this manner the car is advanced up to the working face supported on the temporary track.

As explained above when the working face 100 is advanced, the temporary rails are moved up accordingly. The rail tie connection is easily manipulated so that the method of advancing the track is made simple and expeditious.

I wish it understood that my invention is 105 not limited to any specific construction or arrangement of the parts except in so far as such limitations are specified in the appended claims.

Having thus described my invention, what 110 I claim is:

1. In a device of the kind described, a rail

tie, a fixed abutment on said tie, a rotatable clamping member on said tie, a rail in normal position held down by said clamping member, and a second rail held in horizontal position between said first rail and said abutment.

5 2. In a device of the kind described, a rail tie, a rotatable clip, a rail in vertical position clamped on one side against said tie by said clip, a fixed abutment on said tie on the other side of said rail, and a second rail in horizontal position having its base abutting on said abutment and its ball portion held between the ball portion and base of said first-mentioned rail.

10 15 3. In a device of the kind described, a rail tie, an abutment fixed on said tie, and a clip pivoted on said tie and comprising two parts, one of said parts being adapted to engage the ball portion of a rail in horizontal position 20 and hold the rail against said abutment and the other of said parts being adapted to clamp over the base of a vertical rail.

15 25 4. In a device of the kind described, a rail tie, an abutment fixed on said tie, and a clip pivoted on said tie and adapted to engage the ball portion of a rail in horizontal position and hold the rail against said abutment.

5. In a device of the kind described, a rail

tie, an abutment fixed on said tie, a clip pivoted on said tie and adapted to hold a rail in 30 horizontal position against said abutment, a jaw on said member adapted to support the ball portion of said rail, and a second jaw on said member adapted to hold said ball portion against said first-mentioned jaw.

35 6. In a device of the kind described, a rail tie, an abutment fixed on said tie, and a clip pivoted on said tie having jaws adapted to receive the ball portion of a rail laid on its side with its base against said abutment.

40 7. A rail clip comprising an inclined clamping toe on one side and jaws on the other side adapted to receive the ball portion of a rail laid on its side.

45 8. In a device of the kind described, a rail tie, a fixed abutment on said tie, and a pivoted clip having an inclined clamping toe at one side of its pivot and jaws at the other side, the arrangement being such that the jaws may be turned toward said abutment to 50 receive the ball portion of a rail laid on its side with its base against said abutment, or the clamping toe may be swung over the base of a vertical rail having a horizontal rail wedged between it and said abutment.

WILLIAM A. HUNT.
